CLAIM

I claim the ornamental design for the handheld fan handle, as shown and described.

DESCRIPTION

FIG. 1 is a top perspective view of a handheld fan handle showing my new design;

FIG. 2 is a right side perspective view thereof;

FIG. 3 is a left side perspective view thereof, that opposes the right side perspective view of FIG. 2 thereof;

FIG. 4 is a right side view thereof;

FIG. 5 is a left side view thereof;

FIG. 6 is an overhead top view thereof;

FIG. 7 is a bottom view thereof;

FIG. 8 is a front view thereof;

FIG. 9 is a back view thereof; and,

FIG. 10 is a cross-sectional view of the handheld fan handle taken along line 10-10 of FIG. 8.

The broken lines depict environment that forms no part of the claimed design.
